US0D1093315S

(12) **United States Design Patent** (10) **Patent No.:** **US D1,093,315 S**
(45) **Date of Patent:** **** Sep. 16, 2025**

(54) **JOINT CONNECTOR**

(71) Applicant: **Weiping Xie**, Hunan (CN)

(72) Inventor: **Weiping Xie**, Hunan (CN)

(**) Term: **15 Years**

(21) Appl. No.: **29/898,953**

(22) Filed: **Aug. 3, 2023**

(51) LOC (15) Cl. **13-03**

(52) U.S. Cl.

USPC **D13/133; D13/146**

(58) **Field of Classification Search**

USPC D13/133, 110, 146, 147, 154, 156, 184, D13/199, 123, 124, 158, 134, 159, 160, D13/107, 108; D14/433, 434, 435, 432,

(57) **CLAIM**

The ornamental design for a joint connector as shown and described.

DESCRIPTION

FIG. 1 is a perspective view of a joint connector showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

1 Claim, 8 Drawing Sheets
